Specification for Design.

Patented Oct. 12, 1915.

Application filed July 2, 1915. Serial No. 37,773. Term of patent 3½ years.

To all whom it may concern:

Be it known that I, RUSSELL F. TEALL, a citizen of the United States, residing at Toledo, in the county of Lucas and State of Ohio, have invented a new, original, and ornamental Design for a Tire-Tread, of which the following is a specification, reference being had to the accompanying drawing, forming a part thereof.

The figure is a plan view of a portion of a tire tread showing my new design.

I claim:

The ornamental design for a tire tread, substantially as shown and described.

RUSSELL F. TEALL.
